his attorney.

UNITED STATES PATENT OFFICE.

ROBERT CLARK PIERCE, OF CINCINNATI, OHIO, ASSIGNOR TO THE TOLEDO ELECTRIC WELDER COMPANY, OF CINCINNATI, OHIO, A CORPORATION OF OHIO.

ELECTRIC WELDING-MACHINE.

1,102,797.

Specification of Letters Patent.

Patented July 7, 1914.

Application filed December 31, 1913. Serial No. 809,643.

To all whom it may concern:

Be it known that I, ROBERT CLARK PIERCE, a citizen of the United States, and a resident of Cincinnati, in the county of Hamilton and State of Ohio, have invented a certain new and useful Electric Welding Machine; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

This invention relates particularly to improvements in electric welding machines, and has primarily for its object the provision of a simple and improved form of insulating means for either or both the upper and lower surfaces of the metallic die carrying horns of such machines, whereby mainly to prevent short-circuiting between a surface of the horn and the work should they have contact, such insulating means being secured to a horn in a simple and efficient manner without the use of retaining screws or bands.

The invention is fully described in the following specification, and while, in its broader aspect, it is capable of embodiment in numerous forms, a preferred embodiment thereof is illustrated in the accompanying drawings, in which,—

Figure 1 is a top view of an electric welding machine horn with my insulating means mounted thereon and partly broken away. Fig. 2 is a side elevation thereof. Fig. 3 is an enlarged cross-section on the line α, α in Fig. 2, and Fig. 4 is a cross-section of a slightly different form of horn with both the top and bottom surfaces thereof insulated.

Referring to Figs. 1, 2 and 3 of the drawings, 1 designates a horn of an electric welding machine, which horn is of electrical conductive material, such, for instance, as copper, to enable it to form a part of the lead or current conducting means from the customary transformer (not shown) to the welding die which is carried at the outer end of the horn, as by being mounted in an opening 2 therein. The surface of the horn which is to be insulated, such surface being

the top of the horn shown in Figs. 1, 2 and 55 3, has its side edges extended slightly beyond the body of the horn to form a laterally-projecting bead or rib longitudinally of such edges, as shown at 3.

Mounted over the top surface of the horn 60 with its side edges lapped around the beads 3 thereof is an insulating strip or sheet 4, preferably of fibrous nature, and mounted over such strip to guard and hold it in place is a strip 5, which is preferably of 65 brass, but may be of some other suitable material. The guard-strip 5 has its side edges rolled or bent around the portion of the insulating strip 4, which embraces the beads 3, whereby to firmly hold the insulating strip to the horn and to coöperate with the beads 3 to retain the two strips 4 and 5 in position on the horn. The strips 4 and 5 preferably extend substantially the entire length of the horn, or over any surface 75 thereof with which work is apt to have contact, thus preventing liability of short circuiting due to such contact.

In Fig. 4, 6 designates a rectangular form of horn, which has both the top and bottom 80 surfaces thereof insulated by the application of the insulating and guard strips 4 and 5 to such surfaces. For this purpose the side edges of the lower as well as of the upper surface are made of protuberant 85 or bead form, as shown at 7, to facilitate an embracing of such beads by the respective edge portions of the strips 4 and 5.

It is evident that my improved insulating means may be easily and quickly applied 90 to or removed from the surface of a horn, and is retained in engagement with the horn against accidental removal therefrom without the use of screws, retaining rings or the like. It is also evident that with this form 95 of insulating means, the insulating strips need not be extended entirely around the horn but may be provided merely for the surface with which the work is likely to have contact.

I wish it understood that my invention is not limited to any specific construction or form of the parts, or to the securing of the same to any particular surface of a horn as numerous variations of the invention 105 from the figures of the drawing come within the scope of the invention.

Having thus described my invention, what

I claim as new, and desire to secure by Letters Patent, is,—

In an electric welding machine, a die carrying horn forming an electrical conductor and having a surface thereof provided lengthwise of its side edges with laterally protuberant beads, an insulating strip covering such surface and embracing said beads, and a guard sheet of stiff material covering said insulating material and hav-

ing its side edges embracing said beads and cooperating therewith to retain it and the insulating strip in position on the horn.

In testimony whereof, I have hereunto signed my name to this specification in the 15 presence of two subscribing witnesses.

ROBERT CLARK PIERCE.
